CONCEALED DIAL FOR A COMBINATION LOCK

Herbert G. Ball, Media, Pa.

Application August 4, 1953, Serial No. 26,264

Term of patent 7 years

(Cl. D50—7)

To all whom it may concern:

Be it known that I, Herbert G. Ball, a citizen of the United States, and a resident of Media, Delaware County, State of Pennsylvania, have invented a new, original, and ornamental Design for a Concealed Dial for a Combination Lock, of which the following is a specification, reference being had to the accompanying drawing, forming a part hereof.

Fig. 1 is a front elevational view of a concealed dial for a combination lock, showing my new design.

Fig. 2 is a side elevational view thereof.

Fig. 3 is a top plan view thereof.

I claim:

The ornamental design for a concealed dial for a combination lock, as shown.

HERBERT G. BALL.
